MEANS FOR TRANSMITTING OSCILLATORY MOTION TO WASHING MACHINE AGITATORS

Vernon J. Wooster, St. Joseph, Mich., assignor to
 Nineteen Hundred Corporation, St. Joseph,
 Mich., a corporation of New York

Application June 24, 1943, Serial No. 492,101

11 Claims. (Cl. 68—133)

1
 The present invention relates to a method of and apparatus for transmitting oscillatory motion from a power source to a member to be driven. More particularly, the invention is concerned with the structure and operation of a novel form of transmission which virtually eliminates the lost motion in the operation of the member to be driven.

It is an object of the present invention to provide a novel oscillatory drive mechanism.

It is a further object of the present invention to provide an oscillatory drive mechanism for actuating a member to be driven associated therewith with a minimum of lost motion in its operation and to eliminate operational shocks.

It is a still further object of the present invention to provide an oscillatory drive mechanism, such, for example, as that employed in washing machines or the like for actuating the agitator mechanism thereof.

It is also an object of the present invention to provide an oscillatory drive mechanism embodying means for engaging and disengaging such mechanism from the member to be driven.

A further object of the invention is to provide an oscillatory drive mechanism embodying a reciprocating drive means and having associated therewith various means for coupling said reciprocating member to the member to be driven.

It is a further object of the invention to provide an enclosure or case for a transmission or the like from one member of which all of the parts of the mechanism are supported in operable relation.

It is a still further object of the present invention to provide an enclosure of the character disclosed in which one of the members is of thick-walled or cast construction while the other is formed of relatively thin sheet material such, for example, as a metal stamping.

It is a still further object of the present invention to provide novel means for holding or securing together the members of the enclosure or casing just described.

The present invention contemplates a method of producing oscillatory motion which is substantially free from dwell or lost motion from the operation of a reciprocating member as applied to parts of a washing machine or other similar apparatus. This is brought about by producing a rapid motion throughout the major portion of each stroke of the reciprocating member and slowing up the rate of movement produced as the reciprocating member approaches one extremity of the stroke so as to

gradually merge from one direction of motion into the reverse with a minimum of shock.

In accordance with the general features of the present invention there is provided an oscillatory drive mechanism comprising a reciprocating member, a member to be driven and coupling means associated with said reciprocating means for providing a driving connection between said reciprocating means and said member to be driven, said coupling means being so constructed that it eliminates lost motion in the operation of the member to be driven.

In accordance with other general features of the invention, an enclosure is provided for a transmission or like unit which embodies one member from which all of the parts of the mechanism are supported in operable relation.

In accordance with still other features of the invention, an enclosure is provided which comprises one member of thick-walled or cast construction while another member is formed of relatively thin sheet material such, for example, as a metal stamping, said members being secured together by novel fastening means.

Still other features and advantages of the present invention will be apparent from the following description of the drawings illustrating a number of embodiments of the invention, in which:

Figure 1 represents a vertical sectional elevation of a typical form of apparatus in which the oscillatory drive mechanism of the present invention is particularly advantageously employed;

Figure 2 represents a horizontal section through the upper portion of the oscillatory drive mechanism shown in Figure 1 and showing the arrangement of the parts therein;

Figure 3 corresponds generally to Figure 2 with parts broken away to illustrate the position of the parts of the apparatus in a portion of its operating cycle;

Figure 4 is a partial horizontal section through the apparatus of Figure 1 as seen from the line IV—IV;

Figure 5 is a partial sectional elevation through the apparatus of Figure 4 as seen from the line V—V;

Figure 6 represents a plan view of another embodiment of the oscillatory drive mechanism of the invention which includes additional features not present in the structure of Figures 1 to 3, inclusive;

Figure 7 is a vertical sectional elevation of the device of Figure 6 with parts in elevation;

Figure 8 is a horizontal section through the upper portion of another embodiment of the os-

oscillatory drive mechanism of the invention and corresponding generally with the section shown in Figure 2 of the drawings;

Figure 9 represents a partial horizontal plan view of the shifter mechanism associated with the embodiment of the invention illustrated in Figure 8 of the drawings;

Figure 10 is a partial sectional elevation of the apparatus illustrated in Figure 9 as seen from the line X-X; and

Figure 11 is a vertical sectional elevation of the apparatus of Figure 9 as seen from the line XI-XI.

One embodiment of the present invention is shown in Figure 1 as being adapted to employment in a washing machine comprising a tub 15 which is supported by a suitable base or supporting structure (not shown). Extending vertically through an opening substantially in the center of the base of the tub 15 is a generally cylindrical post 16 which is secured to said tub 15 as by means of the ring member 17 threaded on the base of said post 16. The ring 17 cooperates with gaskets 18 disposed above and below the base of the tub 15 and encircling the opening in the base of tub 15 through which the post 16 extends to prevent leakage therebetween. A washer 19 serves to position the lowermost gasket 18 and abuts the uppermost end of the generally cylindrical boss 20 of the top member which may advantageously take the form of a casting 21 of the case enclosing the transmission unit 14. The lowermost end of the post 16 is also threaded into the internal bore of boss 20 and serves to support the transmission 14 from the base of the tub 15.

Disposed internally of post 16 and in concentric relation thereto is a vertical shaft 22. The shaft 22 is journaled in a sleeve bearing 23 inserted in the uppermost end of post 16 and is encircled by a recessed packing washer 24. The lowermost end of shaft 22 is journaled in a sleeve bearing 25 disposed internally of the bore 26 in the internal boss 27 of the boss portion 20 of top casting 21. A packing washer 28 is recessed in a collar member 29 which surrounds the shaft 22 and abuts the upper end of the boss 27 to support the inverted cup portion of member 30. The member 30, within which is disposed the spring 31, cooperates with the snap ring 32 positioned in an annular groove cut into the shaft 22 to act as a thrust bearing to locate the shaft 22 in proper endwise relation within the post 16.

On the tapered portion 33 at the uppermost end of shaft 22 and supported thereby is an agitator 35. A cap screw 36 threaded into the uppermost end of the tapered portion 33 of shaft 22 provides a means to detachably mount the agitator 35 on the uppermost end of and in fixed relation to said shaft.

Turning our attention now to the transmission unit 14 which embodies the principles of the present invention and is shown in detail in Figures 2 to 5 inclusive of the drawings, it will be noted that said transmission 14 may be actuated by any suitable power source, such, for example, as the motor 38. The motor 38 may be suspended from the under side of the tub 15 or the framework supporting the same by a suitable bracket 39 and bolts 40. The horizontally disposed output shaft 41 of the motor 38 is coupled to shaft 42 of the transmission unit 14 as by means of a suitable flexible coupling 43.

The shaft 42 of transmission 14 is journaled at one end in portion 43 while the other end ex-

tends through portion 44 formed in the wall of the top casting 21 which cooperates with the lower case member 45 to enclose the transmission unit 14. An annular flanged portion 47 on the shaft 42 assists in preventing endwise movement of said shaft 42. A bearing bracket 48 suspended from the top casting 21 of the case enclosing the transmission unit 14 cooperates with portion 43 of top casting 21 to support shaft 42 for rotation. An oil seal 46 encircles shaft 42 in portion 44 to prevent leakage of lubricating medium in which the operating parts run from the case. A plug 47a in the portion 43 on top casting 21 cooperates with flanged portion 47 to maintain shaft 42 in its proper axial position.

A worm 49 may advantageously be cut on said shaft 42 and is adapted to engage the gear 50 which is rotatably mounted upon a stub shaft 51 which extends through the boss 52 in the top casting 21 and is secured thereto by a nut 53 threaded thereon. The gear 50 engages a gear 54 which is secured to a stub shaft 55 supported in endwise relation in the boss 59 of top casting 21 by means of a collar 56 secured to said stub shaft 55 by means of the pin 57 extending therethrough, said collar being supported by a shoulder portion 58 formed internally of said boss 59. Also secured to said boss 59 of the casting 21 is a tubular column 61 which encloses a connecting means 60 secured to the uppermost end of the stub shaft 55 and actuated by the gear 54 thereon. The column 61 may be employed to support a part of the apparatus associated with the washing machine tub 15 such, for example, as a wringer unit or other similar apparatus for operation by the gear 54.

A reciprocating arm 63 is pivotally secured to the underside of the gear 50 by means of a pin 64 which is eccentrically disposed with respect to the center of the stub shaft 51 upon which the gear 50 is rotatably mounted. On the other end of the arm 63 are formed a plurality of gear teeth 65 which engage the teeth of gear 66 mounted upon the shaft 22. The teeth 65 of the arm 63 are maintained in active engagement with the teeth of the gear 66 as by means of a link member 67 which is pivotally secured to one end of the arm 63 by the machine screw 68. The link member 67 is provided at its other end with a collar portion 69 which encircles the shaft 22 and abuts the lower end of the internal boss 27. Thus, as the arm 63 is actuated, the gear teeth 65 thereon are maintained throughout its operation in engagement with the teeth of the gear 66 mounted upon the shaft 22.

The shank portion 70 of the gear 66 is provided with a plurality of vertical slots 71 which are adapted to engage a pin 72 extending radially from the periphery of the shaft 22 adjacent its lowermost end. The gear 66 is adapted to be moved axially of the shaft 22 by means of the clutch finger 73 which registers with an annular slot 74 in the shank 70 of said gear 66 and is secured to the lower end of the pin 75 which is slidably mounted in the boss 76 depending from the upper wall of top casting 21. The pin 75 is urged up or down by the movement of the lever arm 77 an end of which is pivoted in the boss portion 20 of the top casting 21. The lever arm 77 has secured thereto a yoke 78 registering with slots 79 in the periphery of said pin 75 and held in place thereon by a cotter pin 80.

Thus, it will be seen that the movement of the arm 77 will cause the pin 75 to move axially with respect to the boss 76 thereby causing the finger

13 engaging gear 66 to raise or lower said gear 66 either engaging or disengaging one of the slots 71 and the pin 72. When the slot 71 and pin 72 are engaged the shaft 22 will be actuated by the arm 63 and will, in turn, cause the agitator 35 to be oscillated. Conversely, when the slot 71 and the pin 72 are disengaged, the gear 66 will rotate with respect to the shaft 22 but will remain in engagement with the gear teeth 65 of the arm 63.

As will be readily understood from the showing of Figures 2 and 3 of the drawings which illustrate several of the positions of the arm 63 in the course of its cycle of operation, the gear 66 will continue to be rotated in spite of the fact that the reciprocatory movement of the arm 63 diminishes at the end of its cycle of operation. Thus, as the arm 63 approaches the extremities of its reciprocatory cycle and as the pin 64 passes through the point at which the forward movement of the arm changes to a backward movement, or vice versa, the integrally formed gear teeth 65 on the forward end of the arm 63 will be pivoted slightly about the axis of shaft 22, and since they engage the teeth of the gear 66 they will continue to rotate said gear 66 slowly even though the relatively rapid reciprocatory movement of the arm 63 is momentarily halted. As a result of this operation, the shaft 22 when it is engaged with the gear 66 will continue to be oscillated by the arm 63 and the dwell or period of lost motion customarily present in such operations when the reciprocating member changes its direction of movement will be virtually eliminated, as will also the operational shocks which frequently accompany abrupt changes of direction.

The embodiment of the invention illustrated in Figures 6 and 7 is generally similar to that hereinbefore described. The apparatus in question differs principally in that the motor 83 is supported in a U-shaped member 84 with its shaft in a vertical position. The member 84 is domountably secured to a projecting arm 85 advantageously formed as an integral part of the top casting 86 and its boss 87 comprising a part of the case which forms an enclosure for the transmission 88. The motor 83 through its pulley 89, the belt 90 and the pulley 91 of the transmission 88 which is secured to the stub shaft 92 rotatably mounted in the boss 93 of the top casting 86, provides a means for actuating said transmission 88.

The transmission 88 embodies substantially the same gearing arrangement internally thereof as that described in connection with the embodiment of the invention illustrated in Figures 1 to 5, inclusive. The gear 94, at the lower end of stub shaft 92, drives the gear 95 which, in turn, engages the gear 96 for actuating the wringer or other associated attachment for the washing machine and, in addition, carries the eccentrically mounted arm 97 which imparts the oscillatory motion to the shaft 98 concentrically disposed within the vertical post 16 which is threaded into the upper end of the boss 87 of top casting 86.

A link member 99 provided with a collar portion 100 which encircles the shaft 98 and permits link member 99 to pivot thereabout, is pivotally connected to the end of reciprocating arm 97 as by means of the pin 101 on one end of which is threaded a bolt 102. The link member 99, as in the case of the hereinbefore described embodiment of the invention, maintains contact between the integrally formed gear teeth 103 on the end of the reciprocating arm 97 and the teeth of the gear 104 mounted upon the shaft 98.

The lowermost end of the shaft 98 is provided with a splined portion 105 which engages with a cooperating formation on the internal bore of the gear 104 to insure positive driving relation between said gear 104 and said shaft 98 and at the same time to permit the gear 104 to be moved axially with respect to said shaft 98. The gear 104 is adapted to be raised or lowered into or out of engagement with the gear teeth 103 on the arm 97 as by means of the finger 106 which registers with the annular groove 107 cut into the shank portion of said gear 104.

The lever arm 112 which is pivotally mounted in the projections 113 and 114 formed integrally with the arm 85 of top casting 86 is secured to an arm 110 which is pivotally disposed in the slot 111 of the vertical pin 108 mounted in axially slidable relation to the internal boss 109. The shifting of lever 112 will, therefore, cause the finger 106 to raise or lower the gear 104 into or out of engagement with the teeth 103 on the arm 97. The gear 104, by virtue of the splined portion 105, is continually in operable engagement with the shaft 98 but may be completely disengaged from the gear teeth 103 on the reciprocating arm 97 since the shifting mechanism embodying finger 106 will permit the gear 104 to slide downwardly along the splined portion 105 until it assumes the position indicated by the dotted lines in Figure 7 of the drawings.

In spite of the structural differences between the embodiment of the Figures 6 and 7 of the drawings as compared with that of Figures 1 to 5 inclusive, the method of operation of the two transmissions is substantially identical.

The embodiment of the invention illustrated in Figures 8 to 11, inclusive, incorporates the drive mechanism associated with the embodiment of the invention shown in Figures 6 and 7 of the drawings and includes certain additional features of importance. The gear 95 of the transmission unit 116 is actuated by a gear 94 driven by a suitable power source and serves to operate the arm 117 which is eccentrically pivotally mounted upon said gear 95 transmitting oscillatory motion to the shaft 98. On the end of reciprocating arm 117 opposite to that eccentrically mounted upon the gear 95 is disposed a gear 118 freely rotatably mounted on a pin 120 secured to said arm 117 as by means of nut 121 which is maintained in driving engagement with a similar gear 119 mounted upon the lower end of shaft 98.

An over-center toggle 122 is mounted about a pin 130 on arm 117 at a point intermediate the ends thereof to actuate a toothed pawl member 123 adapted to engage one or more teeth of the gear 118 so as to prevent its rotation about pin 120. Pawl 123 is pivoted about a pin 124 being fitted between the plates 125 secured at one end thereof to said pawl 123 by means of the pin 126. A pivotally mounted spacer block 127 is provided between the other ends of plates 125 and is adapted to slidably receive in an aperture therein the pin 128 secured to said toggle 122. A spring 129 surrounding pin 128 assists in the operation of the toggle 122 and permits the pin 128 to move axially in the spacer block 127 as said toggle 122 changes position due to the movement of the arm 117.

The toggle 122 is provided with a pair of vertically extending wing portions 131 and 132 disposed on either side of its pivotal mounting about pin 130. The wing portions 131 and 132 of toggle 122 are adapted, in the course of the operation of the arm 117, to contact one or the

other of a pair of vertical rod members 133 and 134 which are disposed in axially slideable relation to the boss portions 135 and 136 respectively, formed on the outer wall of the top casting 137. The rod members 133 and 134 project through the wall of the top casting 137 and are raised and lowered by the manipulation of the lever arm 138. The lever arm 138 is coupled to an extension 139 rotatably mounted in the vertically extending boss portion 140 formed integrally with the top casting 137 of the case housing the transmission 116 as by means of a coupling 141. The extension 139 is secured to a second over-center toggle assembly 142, the toggle plate 143 of which is secured to the rods 133 and 134 as by means of pivotal pinned and slotted connections.

As the lever arm 138 is manipulated, it will be readily observed that the toggle 143 by virtue of its connection with the rods 133 and 134 will raise one and lower the other of said rods 133 and 134 so that the lowermost end of one or the other of said rods 133 and 134 will contact the wing portion 131 or 132 of the over-center toggle 122 mounted upon the arm 117 as said arm is reciprocated. A spring 144 attached to the projection 145 of the toggle plate 143 and a stationary post 146 mounted upon the exterior of the top casting 137 is provided to hold the toggle 143 in one or the other of its positions after having been shifted by the lever arm 138.

The operation of the transmission 116 will be readily understood from an inspection of the embodiment of the invention illustrated in Figure 8 of the drawings. In Figure 8, the pawl 123 is shown as being in engagement with the gear 118 rotatably mounted about the pin 120 on the end of arm 117. In this arrangement of parts, the arm 117, by virtue of the engagement of the gear 118 with gear 119 which is mounted on the shaft 98, will cause said shaft 98 to be oscillated for the reason that the gear 118 is held against rotation about the pin 120 by the pawl 123. When it is desired to halt the operation of the shaft 98, the operator manipulates the lever arm 138, tripping the toggle assembly 142 so that the rod 134 will be disposed in its lowermost position while the rod 133 will be raised thereby.

As the arm 117, during its cycle of operation, approaches one extremity of its stroke and occupies the position indicated by dotted lines in Figure 8, the toggle 122 will be in the position indicated in dotted lines and designated position A. The toggle 122, as the arm 117 continues to move, will contact the rod 134 in its extended position and will be snapped back into a position corresponding to the dotted lines designated position B, when the arm 117 is in the position shown in solid lines in Figure 8. In this operation of the toggle 122 just described, the pawl 123 which was in engagement with the gear 118 at the beginning and occupying substantially the position indicated in dotted lines and designated position C will be swung back into the position indicated in dotted lines and designated position D, so that it will be completely out of engagement with the gear 118. The gear 118 is now free to rotate about the pin 120 by means of which it is mounted upon the arm 117. Thus, it will be seen that although the gear 118 is in engagement with the gear 119 mounted upon the shaft 98 it will nevertheless fail to actuate the gear 119 and shaft 98 for the reason that as the arm 117 passes through its cycle of operation, 75

the gear 118 will merely trace the teeth of the gear 119.

The exact reverse of the operation just described will take place upon the shifting of the over-center toggle assembly 142 by means of the lever arm 138 so as to cause the rod 133 to assume its lowermost position while the rod 134 is raised. In the actuation of the toggle 122 upon its contact with the extended portion of the pin 134, abutments such, for example, as the stops 147 and 147a on the arm 117 are advantageously provided to prevent the toggle 122 from being swung about the pivot 130 to such an extent that the pin 128 secured thereto will become disengaged from the spacer block 127.

It will be understood that the shifting of the toggle 122 which actuates pawl 123 is illustrated as taking place only when the arm 117 approaches one extremity of its stroke. Obviously, the mechanism may be altered, within the purview of the present invention, so that the engagement of the pawl 123 with the gear 118 may take place at some other suitable interval in the operation of the transmission unit other than that shown. Thus the setting of the rods 133 or 134 by the manipulation of the lever arm 138 does not instantaneously cause the toggle 122 to be tripped.

In the several embodiments of the invention illustrated in Figures 1 to 11, inclusive, of the drawings, it will be noted that different forms of securing means have been employed to fasten the top member, which may advantageously take the form of a casting, to the lower closure member. In each instance, it has been pointed out that all of the operating mechanism of each transmission unit may be supported in operable relation from the top casting. The lower closure member may, in such event, advantageously take the form of a simple closure of relatively light weight thin sheet material stamped or otherwise formed into the required shape to conform to the contour of the top casting.

The transmission case illustrated in Figures 2 to 4 inclusive, of the drawings is provided with a plurality of projections or lugs 149 formed on the top casting 21 and the lower case member 45 thereof to accommodate such forms of fastening means as cap screws, nuts and bolts, or the like which may be employed to secure the lower closure member 45 thereto. In the transmission case illustrated in Figures 6, 8 and 9, the top casting 86 (Figure 6) or 137 (Figures 8 and 9) is provided with a flanged portion 150 extending about the perimeter of the entire casting which engages a similarly flanged portion 152 on the lower case member 151 as will be seen in Figure 7 of the drawings. A plurality of fastening means such, for example, as clips 153 are provided to engage the flanged portions 150 and 152 of the top casting 86 and the lower case member 151 at several points along its perimeter to hold the two members in contact and retain the two pieces comprising the transmission case in tightly closed relation.

It will, of course, be understood that various details of construction and method of operation may be varied through a wide range without departing from the principles of this invention, and it is therefore, not the purpose to limit the patent granted hereon otherwise than necessitated by the scope of the appended claims.

I claim:

1. In a washing machine including a tub, an agitator in said tub and a power source, means

for actuating said agitator from said power source comprising a drive member operated from said power source, reciprocating means actuated by said drive member, coupling means for connecting said reciprocating means and said agitator, means freely rotatably mounted on said reciprocating means for driving the agitator through said coupling means, and pivotally mounted means associated with said reciprocating means for selective engagement with said rotatably mounted means to hold the same in fixed relation to said reciprocating means to drive said agitator and disengagement from said rotatably mounted means to stop said agitator.

2. In a washing machine including a tub, an agitator in said tub and a power source, transmission means for controlling the operation of said agitator from said power source comprising a drive member operated from said power source, reciprocating means actuated by said drive member, coupling means for connecting said reciprocating means and said agitator, means for driving said agitator through said coupling means, means rotatably mounted on the reciprocating means engaging said agitator driving means, and means pivotally mounted with respect to said reciprocating means for selective engagement with said rotatably mounted means to hold the same in fixed relation to said reciprocating means to drive said agitator driving means, and disengagement from said rotatably mounted means to stop said agitator driving means.

3. In a washing machine including a tub, an agitator in said tub and a power source, transmission means for controlling the operation of said agitator from said power source comprising a drive member operated from said power source, reciprocating means actuated by said drive member, a toothed member for actuating said agitator, a second toothed member freely rotatably mounted upon the reciprocating member for driving the first-mentioned toothed member, means pivotally mounted upon said reciprocating means for selective engagement with said rotatably mounted toothed member to hold the same in fixed relation to said reciprocating means to drive said agitator and disengagement from said rotatably mounted toothed member to stop said agitator, and mechanically operated control means for operating said pivotally mounted means.

4. In a washing machine including a tub, an agitator in said tub and a power source, transmission means for controlling the operation of said agitator from said power source comprising a drive member operated from said power source, reciprocating means actuated by said drive member, a drive gear for said agitator, a second gear freely rotatably mounted upon the reciprocating member and meshing with the agitator gear, and mechanically operated means associated with said reciprocating means for selective engagement with said rotatably mounted gear to hold the same in fixed relation to the reciprocating means to drive said agitator and disengagement from said rotatably mounted gear to stop said agitator.

5. An oscillatory drive mechanism comprising a drive member, a member to be driven, reciprocating means secured to said drive member, coupling means for connecting said reciprocating means and said member to be driven, and pivotally mounted means associated with said reciprocating means for selective engagement with and disengagement from said coupling means.

6. An oscillatory drive mechanism comprising a drive member, a member to be driven, reciprocating means secured to said drive member, means freely rotatably mounted on said reciprocating means for driving the member to be driven, means pivotally mounted with respect to said reciprocating means for selective engagement with said rotatably mounted means to hold the same in fixed relation to said reciprocating means to drive said member to be driven, and means pivotally mounted with respect to said reciprocating means for selective engagement with and disengagement from the rotatably mounted means.

7. An oscillatory drive mechanism comprising a power source, reciprocating means actuated by said power source, a member to be driven, coupling means for connecting said reciprocating means and said member to be driven, pivotally mounted means associated with said reciprocating means for selective engagement with and disengagement from said coupling means, and mechanically operated control means for actuating said pivotally mounted means.

8. An oscillatory drive mechanism comprising a power source, reciprocating means actuated by said power source, a gear freely rotatably mounted upon said reciprocating means, a gear to be driven engaging said freely rotatably mounted gear, means for maintaining said gears in engagement, pivotally mounted means for disengageably contacting said freely rotatably mounted gear so as to prevent its rotation, and means associated with said reciprocating means for selectively engaging and disengaging said contacting means from said freely rotatably mounted gear.

9. In a washing machine including a tub, an agitator in said tub and a power source, means for actuating said agitator from said power source comprising a drive member operated from said power source, reciprocating means actuated by said drive member, a gear rotatably mounted upon said reciprocating means adjacent the free end thereof, a shaft supporting said agitator, a gear secured to said shaft, a link member pivotally connected to said shaft and the free end of said reciprocating means for maintaining the rotatably mounted gear and the agitator gear in engagement, pivotally mounted means for engaging the rotatably mounted gear to prevent its rotation and to cause the agitator shaft to be oscillated by said reciprocating means, and mechanically operated control means for engaging and disengaging said pivotally mounted means with respect to said rotatably mounted gear.

10. An oscillatory drive mechanism comprising a reciprocating member, a member to be driven, means for coupling said member to be driven and said reciprocating member, said coupling means including driving means freely rotatably mounted upon said reciprocating member, pivotally mounted means associated with said reciprocating member for selectively engaging said driving means to prevent its rotation and to transmit oscillatory motion to said member to be driven, and mechanically operated control means for selectively engaging and disengaging said pivotally mounted means and said driving means.

11. An oscillatory drive mechanism comprising drive means, a member to be driven, reciprocating means actuated by said drive means for producing a rapid motion of the member to be driven during the major portion of each stroke in the reciprocating cycle of said reciprocating means, pivotal means associated with said recip-

11

rocating means for slowing up the rate of movement of the member to be driven as the reciprocating member approaches the extremity of its stroke, means for latching said pivotal means in fixed relation to said reciprocating means, and manual control means for engaging and disengaging said latching means from said pivotal means when the reciprocating means reaches a predetermined position in its stroke.
